[57] CLAIM

The ornamental design for a light assembly for motor vehicle, substantially as shown and described.

DESCRIPTION

FIG. 1 is a perspective view of a light assembly for motor vehicle, showing my new design;

FIG. 2 is a right side elevational view thereof on an enlarged scale;

FIG. 3 is a front elevational view thereof on an enlarged scale;

FIG. 4 is a top plan view thereof on an enlarged scale;

FIG. 5 is a rear elevational view thereof on an enlarged scale; and

FIG. 6 is a bottom plan view thereof on an enlarged scale.

FIG. 1**FIG. 2****FIG. 3****FIG. 4****FIG. 5****FIG. 6**
